W. LANE

VALVE ADJUSTER

Filed May 13, 1926

UNITED STATES PATENT OFFICE.

WILLIAM LANE, OF DAYTON, OHIO.

VALVE ADJUSTER.

Application filed May 13, 1926. Serial No. 108,844.

This invention relates to explosive engines and more particularly to adjustable tappets for the valve stems of puppet valves to enable the valve to be adjusted for efficient 5 operation and to compensate for wear.

While the present invention is applicable to the stems of puppet valves of various sizes and for different styles and types of motors, it has been especially designed to 10 overcome the difficulty encountered in the use of a popular make of low-priced automobile motors, which as furnished by the manufacturer has no provision for adjustment, and no means for compensating for 15 wear. In this particular style of motor, the valve stems are operated by push rods which are slightly greater in diameter than the diameter of the valve stem. The constant 20 repeated impact of the push rods upon the ends of the valve stems cause the push rods to be worn or swedged into concave form on their extremities, within which concavities the ends of the valve stems continue to engage. To replace such push rods, necessi- 25 tates dismantling the motor. The particu- 30 lar type of popular motor referred to is so designed that there is but a very limited space between the valve stem guide or boss upon the cylinder block, and the push rod 35 guide or boss upon the engine frame. This space is insufficient to accommodate the usual type of adjustable tappet devices. Conse- 40 quently, the adjusting means for the present adjustable tappet head is located interiorly 45 of the valve spring.

In the present invention, there is contemplated an adjustable tappet head, screw threaded upon the end of the valve stem, and so adjustable thereon to compensate for 45 wear and to enable the proper adjustment of the valve in relation with its seat. This tappet head carries a peripheral flange or collar upon which the valve spring abuts. The tappet head projects inwardly within 50 the valve spring and is longitudinally split to enable its contraction upon the screw threaded stem with which it is engaged. The exterior of the split portion of the tappet head is of tapered or conical formation 55 and exteriorly threaded to receive a compression nut. Because of the lack of space, this nut is arranged within and is surrounded with the valve spring.

The object of the invention is to simplify 55 the construction as well as the means and mode of operation of adjustable tappets for

engine valves and the like, whereby they will not only be cheapened in construction, but will be more efficient in use, positive in operation, enable uniform action of the 60 valves and unlikely to get out of repair.

A further object of the invention is to provide an adjustable tappet device applica- 65 ble to explosive engines or automobile motors wherein the available space intermediate the valve stem and push rod guides is insufficient to accommodate the usual form of adjustable tappet device.

A further object of the invention is to enable the adjustment of valves of a popular 70 type of automobile motor without the necessity for dismantling the motor for replacement of push rods.

With the above primary and other incidental objects in view as will more fully appear in the specification, the invention consists of the features of construction, the parts and combination thereof, and the mode of operation or their equivalents as herein- 75 after described and set forth in the claims. 80

Referring to the accompanying drawing, wherein is shown the preferred, but obviously not necessarily the only form of embodiment of the invention, Fig. 1 is a side elevation partly in section of a portion of an automobile motor, illustrating the puppet valves and actuating means therefor, to which the present invention has been applied. Fig. 2 is an enlarged sectional view of the adjustable tappet construction forming the sub- 85 ject matter hereof. Fig. 3 is a side elevation of the adjustable tappet construction shown in Fig. 2, and Fig. 4 is a top plan view thereof, with the valve stem in section.

Like parts are indicated by similar characters of reference throughout the several views.

Referring to the accompanying drawings, 1 indicates a portion of an automobile motor or the like, in which are mounted, the 100 puppet valves 2—2. The puppet valves are provided with dependent valve stems 3 and are actuated in proper time by reciproca- 105 tory push rods 4 mounted in guides or bosses 5 and actuated by cams 6 upon a rotary cam shaft. Surrounding the dependent stems 3 of the valves are retracting springs 7, by which the valves are returned to their seats, and against the resistance of which the valves are lifted by the operation of the 110 push rods.

As furnished by the manufacturer at the

present time, the reciprocatory push rod 4 has direct contact with the end of the valve stem 3 for lifting the valve from the seat. As the end of the push rod 4 wears through 5 long use, the relation of the valve 2 with the seat changes. The present invention is intended to provide means for compensating for wear and for enabling the proper adjustment of the valves in relation with the 10 seats for efficient operation.

To this end, the valve stems 3 are somewhat shortened and threaded throughout a portion of their length as at 8. Screw threaded upon this extremity of the valve 15 stem 3 is a tappet head 9, carrying a peripheral flange or collar 10 upon which the retracting spring abuts. The collar or flange 10 may be formed integral with the tappet head 9, but is preferably independently 20 formed by stamping and rests upon a peripheral shoulder 11 formed upon the tappet head 9. The portion of the tappet head 9 projecting beyond the flange or collar 10 and within the retracting spring 7 is some- 25 what tapered or of conical formation and is interiorly threaded for engagement with the screw threads 8 of the valve stem, and is also exteriorly threaded for engagement of a compression or lock nut 12. This 30 threaded conical portion of the tappet head 9 is longitudinally slotted at 13, to permit the contraction or compression of this threaded tapered portion of the tappet head upon the threaded portion 8 of the valve 35 stem under the influence of the lock nut 12. The lock or compression nut 12 is thus located within and surrounded by the retracting spring 7, and is accessible for adjustment between the successive turns or con- 40 volutions of the spring. The lower portion of the tappet head 9 beyond the flange or collar 10 is formed with flat surfaces, or is preferably square to receive a wrench or 45 spanner to enable the rotation of the tappet head to adjust it upon its threaded connection with the valve stem to increase or decrease the effective length of the valve stem as may be necessary. This adjustment can be effected only by first releasing the lock or 50 compression nut 12. In order that the valve stem 3 may be held against rotation during adjustment of the tappet head 9, the stem is preferably provided with a hole 14 at a mid-length point, through which a tool or 55 wire may be thrust to hold the valve and its stem while the tappet head is being rotated thereon. When the adjustment has been completed, the tappet head is again locked by the tightening of the lock or compression 60 nut 12 upon the threaded conical portion of such head 9, thereby again compressing the split portion of the head into tight secure engagement with the threaded portion 8 of the valve stem.

65 It will be thus seen that the tappet may

be adjusted to compensate for wear or to adjust the relation of the valve to its seat for efficient operation, without the use of a valve lifter, and without the use of any tool or device for contracting and holding the spring 70 7. The adjustment of the valve necessitates the use of no special tools and the necessity for dismantling the motor for replacement of push rods 4 when the latter may have become worn or battered at their ends is entirely obviated. One of the important features of the invention particularly as applied to the popular form of motor mentioned, wherein the space between the valve stem 75 guides and push rods is quite limited, is that a considerable portion of the added adjusting feature and the lock nut therefor are located wholly within the retracting spring, so that the full length of the original spring 80 may be utilized and yet the adjusting device 85 applied within the limited range afforded in the particular motor construction.

From the above description it will be apparent that there is thus provided a device of the character described possessing the particular features of advantage before enumerated as desirable, but which obviously is susceptible of modification in its form, proportions, detail construction and arrangement of parts without departing from the principle 95 involved or sacrificing any of its advantages.

While in order to comply with the statute the invention has been described in language more or less specific as to structural features, it is to be understood that the invention is 100 not limited to the specific details shown, but that the means and construction herein disclosed comprises the preferred form of several modes of putting the invention into effect and the invention is, therefore, claimed 105 in any of its forms or modifications within the legitimate and valid scope of the appended claims.

Having thus described my invention, I 110 claim:

1. In a valve adjuster of the character described, the combination with a screw threaded valve stem, and a helical valve spring surrounding the stem, an adjusting member screw threaded upon the valve stem, and projecting within the spring, a spring seat collar carried by the adjusting member upon which the spring abuts and a lock nut enclosed within and surrounded by said spring and by its adjustment securing the adjusting 115 member in its adjusted relation with the valve stem.

2. In a valve adjuster for puppet valves, the combination with a valve stem, a helical spring surrounding the valve stem, of a tappet head adjustable upon said stem, and projecting within said spring, an abutment collar for the valve spring carried by the tappet head, and locking means for securing the tappet head in its adjusted position upon the 120 125 130

stem, said locking means being enclosed within and surrounded by the valve spring.

3. In a valve adjuster for puppet valves, the combination with a valve stem, a helical spring surrounding the valve stem, of a tappet head adjustable upon said stem, and projecting within said spring, an abutment collar for the valve spring carried by the tappet head, said tappet head being exteriorly threaded and longitudinally split and a lock nut threaded upon the longitudinally split portion of the tappet head for contracting the head upon the stem in its adjusted position, said lock nut being located within and surrounded by said spring.

4. In a valve adjuster for puppet valves, the combination with a screw threaded valve

stem, and a helical spring surrounding the stem, of a tappet head having screw threaded engagement with the valve stem and adjustable thereon, said tappet head being exteriorly tapered, the tapered portion thereof being screw threaded and longitudinally split to enable the contraction of the split portion of the head into locking engagement with the stem, said tappet head projecting within the helical valve spring and a lock nut engaging the tapered threaded portion of the tappet head and enclosed within and surrounded by said spring.

In testimony whereof, I have hereunto set my hand this 4th day of May A. D. 1926.

WILLIAM LANE.
